DESIGN FOR A FLOWER HOLDER

Arthur Craig de Angelis and John P. Croasdale,
Jr., Philadelphia, Pa., assignors to Lewis P.
Weil, Philadelphia, Pa.

Application September 22, 1938, Serial No. 80,034

Term of patent 3½ years

To all whom it may concern:

Be it known that we, Arthur Craig de Angelis and John P. Croasdale, Jr., citizens of the United States, residing in Philadelphia, county of Philadelphia, and State of Pennsylvania, have invented a new, original, and ornamental Design for a Flower Holder, of which the following is a specification, reference being had to the accompanying drawing, forming part thereof.

Fig. 1 is a front elevation of a flower holder showing our new design.

Fig. 2 is a side elevation of the same.

Fig. 3 is a top plan view of the same.

We claim:—

The ornamental design for a flower holder, as shown.

ARTHUR CRAIG DE ANGELIS.
